CARL-OLOV LINDBERG

ELECTRIC AIR HEATER

Filed June 11, 1924

Inventor
Carl-Olov Lindberg
By *Henry Orth Jr.*
Atty.

UNITED STATES PATENT OFFICE.

CARL-OLOV LINDBERG, OF STOCKHOLM, SWEDEN.

ELECTRIC AIR HEATER.

Application filed June 11, 1924. Serial No. 719,328.

To all whom it may concern:

Be it known that I, CARL-OLOV LINDBERG, a citizen of the Kingdom of Sweden, residing at Stockholm, Sweden, have invented new and useful Improved Electric Air Heaters, of which the following is a specification.

This invention relates to electric air-heaters, and more particularly to air-heaters for use in connection with explosive engines using gasolene or a similar light fluid as the motive power, to supply the carbureter with heated air, with the object in view to facilitate starting in cold weather or prevent the carbureter from being burnt up due to 15 turn explosions from the engines.

The object of this invention is to provide an air-heater of the said kind which permits of proper adjustment of the passage of air through the heater in a simple and efficient way, and further permits an automatic adjustment of the air with change in electric current.

In the accompanying drawing an embodiment of the invention is illustrated.

Figure 1 is a longitudinal section through the air-heater proper; Fig. 2 is a front elevation of a valve belonging to the heater; and Fig. 3 is a longitudinal section through a common controlling mechanism for said

valve and for the electric current.

The air-heater comprises a tube 1, Fig. 1, adapted to be attached to the air-intake pipe 2 of the carbureter of an explosive engine using gasolene or a similar fuel as the motive power. Inserted in said tube is an electric heating coil 3 and a valve or damper 4.

The tube may preferably be coated on its inner surface with a heat-insulating material, such as asbestos. The heating-coil 3 comprises a suitable wire or tape wound as a cone the largest diameter of which corresponds to the inside diameter of tube 1. The coil is carried by two pins 5, 6 secured to 45 the wall of tube 1, which serve at the same time as binding posts.

Due to the fact that the coil is freely suspended, the heat thereof will be transmitted directly and instantaneously to the air passing through the tube 1, and the conical shape of the coil will secure a uniform heating of said air, while preventing the various turns of the coil from coming into contact with one another due to vibrations of the engine or vehicle.

The valve 4 is adapted to be kept closed

when the engine is to be started. This will prevent the air first heated by the coil from escaping into the atmosphere before the engine has reached a certain speed and the suction of air by the engine is initiated. The valve 4 may yet be formed with radially extending apertures 7 allowing a restricted amount of air to pass even in the closed condition of the valve. The plate 4 may be 63 adjusted in different positions to vary the air-passage through the tube. As soon as the engine has been started the valve should be completely opened. The movement of the valve may be controlled by a spring operated handle 8.

The means for controlling the valve may, preferably, be combined with an interrupter controlling the supply of current to the coil 3 so that the closure of the electric circuit 75 and the closure of the valve may be effected by one and the same manipulation. Such a combined controlling mechanism is shown in the drawing. Attached to the valve shaft 11 is a lever 12 which in the open condition 80 of the valve is in the position shown by dotted lines 12¹. The valve may be closed by pulling at the button 8 the stem 9 of which is connected to the lever 12 by a Bowden cable 10.

Figs. 1 and 3 show the position of the valve and the lever 12 when the button 8 is pulled out. The button, when released, is restored automatically to its innermost position and causes thereby the valve to close. 90

This is due to the effect of the springs 13 and 14. The stem 9 of the button 8 carries a contact clip 15 cooperating with two metal plates 16 serving as contact surfaces which are carried inside a sleeve 18 by means of 95 suitable insulating blocks 17. The closure of the electric circuit is effected by the clip 15 which is caused due to a pull at the button 8 to move upwards into between the disks 16 to the position shown by full lines in 100

Figs. 3. The current may then pass from the two metal plates 16 to the clip 15. The plates are connected to each other by a conductor (not shown) and are further connected, by the conductor 20 to the binding post 21 connected to one terminal of a heating battery (not shown) the other terminal of which is connected to one of the pins 5, 6. The other pin is connected, as by the engine frame, to the sleeve 18, the clip 15 being electrically connected to the engine frame by way of the spring 13 and the but-

ton stem 9. Immediately upon the release of the button 8, the contact clip 15 will be restored to its normal position (as shown by dotted lines 15¹) under the action of its spring 13. The circuit is now open.

The contact plates 16 are carried by a disk or the like 22 and insulated therefrom by an insulating member 23. The disk 22 is adapted to be attached to an appropriate part 24 of the vehicle.

Air passing through the tube 1 is heated by the coil 3 and, due to the conical form of the coil, said heating will take place uniformly over the entire area of the tube.

15 The heated air entering the carburetor will enable the starting to be effected easily and instantaneously even in cold weather and with the use of a relatively heavy fuel as the motive power.

20 This will remove a plurality of heavy inconveniences, inherent to vain starting attempts. Thus, the lubricating oil will never be mixed with fuel which, as a result of such vain starting attempts, will escape in non-vaporized state from the carburetor to be thereafter drawn into the cylinders and from thence beyond the pistons down into the crank casing. The starting storage battery will be freed from the over loading 30 to which it is subjected when it has to supply an engine which is heavy to start due to bad vaporization of the fuel, with current during a longer period.

As a result of the immediate starting of the engine the liability of the starting mo-

tor to be prematurely worn out or burnt will be dispensed with. Furthermore, it is to be noted that the heating coil forms a good explosion guard which may be further improved by inserting a wire net below 40 the coil.

It is further to be noted that modifications may be made without departing from the principle of the invention. For instance, the coil 3 may have a different form from that shown, as the form of a flat coil. In such case, however, the danger of short-circuit between the various turns is considerably increased and the total length of the coil considerably reduced.

When applying the heater to engines having no electric starting machinery, the interrupter may, preferably, be provided with locking means permitting the current to remain closed even after the button 8 is released.

50 What I claim is:

In an air-heater for explosive engines, a tube, a damper in said tube adapted to control the flow of air therethrough, an electric 60 heating coil in said tube, a manually operable switch adapted to control the circuit of said coil and a mechanical connection between said switch and said damper adapted to close the damper at the opening of said 65 circuit.

In testimony whereof I have signed my name.

CARL-OLOV LINDBERG.
